CLAIM

The ornamental design for a spinal implant, as shown and described.

DESCRIPTION

FIG. 1 is a top perspective view of a first embodiment of a spinal implant showing my new design;

FIG. 2 is a bottom perspective view thereof;

FIG. 3 is a first side elevation view thereof;

FIG. 4 is a second side elevation view thereof;

FIG. 5 is a rear elevation view thereof;

FIG. 6 is a front elevation view thereof;

FIG. 7 is a top plan view thereof;

FIG. 8 is a bottom plan view thereof;

FIG. 9 is a top perspective view of a second embodiment of a spinal implant showing my new design;

FIG. 10 is a bottom perspective view thereof;

FIG. 11 is a first side elevation view thereof;

FIG. 12 is a second side elevation view thereof;

FIG. 13 is a rear elevation view thereof;

FIG. 14 is a front elevation view thereof;

FIG. 15 is a top plan view thereof; and,

FIG. 16 is a bottom plan view thereof.

The broken lines immediately adjacent to solid lines depict unclaimed boundaries that form no part of the claimed design. The remaining broken lines shown in the figures are included for the purpose of illustration and form no part of the claimed design.
